UNITED STATES PATENT OFFICE

2,017,106

WATERPROOF SHEET MATERIAL FOR
BUILDING CONSTRUCTION

Harry N. Sandell, Boston, Mass., assignor to H. N. Sandell Company, Boston, Mass., a corporation of Massachusetts

Application December 5, 1933, Serial No. 701,006

7 Claims. (Cl. 154—53)

This invention relates to improvements in waterproof sheet materials and particularly to a sheet material adaptable for universal use in waterproofing building construction.

- 5 Sheet waterproofing material in various forms is required and utilized in numerous places in every type of building construction to prevent water from seeping into the structure. Present day outside masonry walls for buildings are particularly susceptible to water seepage and much damage may occur within the building to interior decorations unless the outside wall is properly flashed. In recent years much study has been given to this problem and many types of interlocking through-wall flashings have appeared, but practically all flashings of this type have serious structural defects and are open to criticism. Flashings of this character are usually constructed in their entirety of sheet metal, certain of which corrode easily and causes the stone-work to become discolored. Flashing that is often referred to as interlocking wall flashing requires an excessive amount of space because it necessarily is embedded in the binding material between courses of masonry and an extremely wide joint is formed. It is often difficult to properly embed interlocking flashing in binding material because of the formation of the flashing and the binding material often fails to enter recesses provided therefor in the flashing.

The primary object of this invention is to provide a practical inexpensive waterproof sheet material which may be used universally throughout the structure of a building wherever water is liable to seep into the structure.

Another object of the invention is to provide a waterproof sheet material of the character described constructed of materials which will not be affected by expansion and contraction, or by acids in smoke, or by chemical action which may be set up by materials which may contact therewith and which furthermore will not discolor stonework or other masonry between layers of which it may be utilized as a flashing.

Another object of the invention is to provide a waterproof sheet material which will be easy to apply wherever required, which does not require soldering, and which will make an effective bond with any material.

Still another object of the invention is to provide a waterproof sheet material having a metallic member embodied therein which will function to stiffen the material and also act to prevent an inner layer of a waterproofing substance from

creeping or squeezing laterally when the sheet material is subjected to excessive pressure.

The invention consists in a waterproof sheet material for use in building construction as set forth in the following specification and particularly as pointed out in the claims thereof.

Referring to the drawing:

Fig. 1 represents a plan view of a piece of waterproof sheet material embodying my invention, an outer layer of said material being broken away to more clearly illustrate the inner construction.

Fig. 2 is an enlarged detail sectional view taken on the line 2—2 of Fig. 1.

Fig. 3 is a detail view similar to Fig. 2 illustrating the waterproofing material embedded in the binding material of a masonry wall between adjacent courses of masonry.

Fig. 4 is a vertical section through a masonry wall illustrating several locations where the waterproofing material of this invention may be used effectively as a flashing.

Figs. 5 and 6 are plan views similar to Fig. 1 illustrating modified embodiments of my invention.

Like numerals refer to like parts throughout the several views of the drawing.

In the drawing referring particularly to Figs. 1 to 4 inclusive, 10 represents a portion of a strip of waterproof sheet material of this invention which may be of any desired length and width.

The sheet material 10 embodies therein superposed layers 11 of a strong closely woven fabric impregnated with a suitable waterproofing substance preferably liquid asphalt or equivalent

material which is preferably dried to such an extent that the fabric may be readily handled without undue sticking. Interposed between the layers of impregnated fabric 11 is a layer of a suitable waterproofing substance 12 preferably asphalt in plastic form which may vary in thickness according to the purpose for which the material may be utilized. Embedded in the layer of waterproofing material 12 is a suitable stiffening

and reinforcing material consisting of wire fabric 13 and it is evident that the size of the wire of which the fabric 13 is constructed and the mesh of this fabric may vary according to the purpose for which the waterproof sheet material may be utilized.

The various layers of material 11, 12, and 13 are all compressed tightly together and caused to adhere one to another and in certain instances as, for example, when the material is to be utilized as a through-wall flashing to form a

50 55

water cut-off course in a masonry wall it is desirable that the layers of impregnated fabric 11 shall be depressed into the spaces between the strands of the fabric 13 in order that ridges 14 and depressions 15 may be formed upon both upper and lower surfaces of the sheet material 10.

In Fig. 4 I have illustrated a masonry wall A in transverse section and the material 10 of this invention may be utilized effectively as a flashing at a, b, and c in said wall to prevent the downward seepage of water therethrough. The material 10 may also be used at other locations in the wall A, not illustrated in the drawing, but well known to those skilled in the art, as, for example, above lintels and beneath window sills. When used at such locations the material 10 is embedded in mortar 16 which is utilized to bind the adjacent courses of masonry together and this binding material enters the depressions 15 provided in the upper and lower surfaces of the material 10 between the ridges 14 thereof and acts to bond the flashing material and masonry structure together and prevent a relative movement therebetween in a horizontal plane. Wherever it is desirable that flanges shall be provided for strips of flashing as is the case at the locations b and c the wire fabric 13 acts as a stiffening and reinforcing material for said flange. Furthermore, wherever the weight of the wall above the flashing strips a, b, and c might tend to squeeze the layer of waterproofing material 12 outwardly from between the layers of fabric 11 the wire fabric 13 will act to prevent such seepage laterally toward the exterior of the wall.

Another use for the waterproofing material 10 of this invention is illustrated at d, Fig. 4. At this location the material 10 may be used in a well-known manner as a roofing material upon the surface of the roof or a flashing material at the junction of the roof and the wall and any number of layers of the material 10 may be used as may be desired.

The material 10 may, furthermore, be used as a membrane at e, Fig. 4, at the bottom of the wall A and adjacent to the basement floor of the building to prevent seepage into the basement between the foundation B and footing C and at other locations around said foundation where a waterproofing material may be required.

In Fig. 5 I have illustrated a modified embodiment of my invention in which 17 represents a portion of a strip of waterproof sheet material embodying therein superposed layers of fabric 18 impregnated with liquid asphalt or equivalent material and dried. Interposed between the layers of impregnated fabric 18 is a layer of plastic asphalt 19 in which is embedded a strip of sheet material 20 which is perforated at 21 throughout its entire area. The various layers of material 18, 19, and 20 are all compressed tightly together and caused to adhere one to another in substantially the same manner as are the layers comprising the strip of sheet material 10 and preferably slight depressions will be formed in the material 17 upon opposite sides of the perforations 21.

In Fig. 6 still another modified embodiment of the invention is illustrated in which sheet material 22 is formed of superposed layers of fabric 23 impregnated with liquid asphalt or equivalent material, and interposed between the layers of fabric 23 is a layer of plastic asphalt 24 in which is embedded a strip of sheet metal 25. The layers of material 23, 24, and 25 are all compressed

closely together and caused to adhere one to another.

In all of the various embodiments of this invention the metal member acts to stiffen and reinforce the material and as in each instance this metallic member is embedded in asphalt corrosion is prevented and when the material is embedded in the wall of a masonry structure to constitute a water cut-off course in the wall stains that are usually caused by corrosion from a metallic flashing member are prevented.

The material of this invention may be used everywhere in a building where seepage of water may occur and will effectively resist corrosion wherever utilized.

It will be understood that any of the well-known forms or compositions of asphalt may be utilized as the waterproofing material or any other equivalent material known in the art having the characteristics of asphalt.

I claim:

1. A waterproofing material of the character described comprising superposed layers of fabric impregnated with a liquid waterproofing substance and dried, a layer of a plastic waterproofing substance interposed between said layers of fabric, and a perforated metallic stiffening material embedded in said layer of plastic waterproofing substance.

2. A waterproofing material of the character described comprising superposed layers of woven fabric impregnated with asphalt and dried, a layer of asphalt in permanent plastic form interposed between said layers of fabric and filling the space therebetween, and a wire fabric embedded in said layer of plastic asphalt.

3. A flashing comprising superposed layers of sheet material impregnated with a waterproofing substance and dried, a layer of a plastic waterproofing substance interposed between said layers of sheet material, and a perforated metallic stiffening material interposed between said layers of sheet material and embedded in said plastic waterproofing substance, said layers of sheet material being depressed into the perforations of said sheet material and forming depressions in the surface of said flashing.

4. A flashing comprising superposed layers of woven fabric impregnated with liquid asphalt and dried, a layer of plastic asphalt between said layers of fabric, and a wire fabric interposed between said layers of other fabric and embedded in said plastic asphalt, said layers of fabric being depressed into the spaces between the strands of said wire fabric and forming ridges and depressions in the surface of said flashing.

5. A flashing material for masonry walls comprising outer layers of textile fabric impregnated with a liquid waterproofing material and dried to provide waterproof outer layers and a relatively non-adhesive outer surface, an intermediate layer of plastic asphalt interposed between said outer layers, and a metal reinforcing material embedded in said layer of plastic asphalt.

6. A flashing material for masonry walls comprising outer layers of woven textile fabric impregnated with a liquid waterproofing material and dried to provide waterproof outer layers and a relatively non-adhesive outer surface, an intermediate layer of plastic asphalt interposed between said outer layers, and a woven wire fabric embedded in said layer of plastic asphalt.

7. A flashing material of the character described comprising outer layers of woven textile fabric impregnated with liquid asphalt and dried

to provide waterproof outer layers and a relatively non-adhesive outer surface, a continuous layer of plastic asphalt interposed between said outer layers of fabric and filling the space therebetween, and a woven wire fabric embedded in said layer of plastic asphalt, said outer layers of

fabric being depressed from opposite sides of said sheet material into the spaces between the strands of wire fabric and forming ridges and depressions in the outer surfaces of said material.

HARRY N. SANDELL.
